CLEARANCE MARKER LIGHT FOR VEHICLES

William L. Mappes, Cincinnati, Ohio, assignor to Duplan Corporation, Winston Salem, N.C., a corporation of Delaware

Filed Dec. 5, 1960, Ser. No. 63,112

Term of patent 14 years

(Cl. D48—32)

FIGURE 1 is a top plan view of a clearance marker light for vehicles showing my new design.

FIGURE 2 is a front elevational view thereof.

FIGURE 3 is an end view thereof.

FIGURE 4 is an enlarged cross-sectional view taken along line 4—4 of FIGURE 1.

FIGURE 5 is an enlarged cross-sectional view taken along line 5—5 of FIGURE 1.

FIGURE 6 is an enlarged fragmentary sectional view taken along line 6—6 of FIGURE 3.

I claim:

The ornamental design for a clearance marker light for vehicles, substantially as shown.
